UNITED STATES PATENT OFFICE

ROBERT W. FIEROH, OF CHICAGO, ILLINOIS

HEATING DEVICE FOR CONCRETE PLANTS

Application filed December 6, 1930. Serial No. 500,458.

This invention relates to the art of concrete mixing plants, and constitutes a continuation in part of an application heretofore filed by me on the 8th day of July, 1929, Serial No. 5 376,792, Letters Patent No. 1,802,840, April 28, 1931.

In the apparatus disclosed in my aforesaid application there is mounted on a portable platform a material bin divided by a false bottom into a lower compartment adapted to contain bags of cement and an upper compartment or hopper adapted to receive mineral, this latter, in the construction shown, employing a central vertical partition providing on one side thereof a hopper for crushed stone and on its other side a hopper for sand. Extending upwardly through one end of the material bin is a vertical conveyor casing housing an endless bucket elevator and equipped at its upper end with a hinged discharge spout by which the material may be delivered into either of the underlying crushed stone and sand hoppers. The two hoppers are equipped at their bottoms with discharge gates or valves by which the mineral ingredients are delivered through a guide chute into a mixer located in the lower compartment.

In a concrete mixing plant of this type, 30 which operates out of doors, it is desirable, and practically necessary, to provide some means for maintaining the mineral in the hopper or hoppers at a temperature above the freezing point, in order that the apparatus 35 may function in sub-freezing weather; and the object of the present invention is to provide a very simple and highly efficient means for heating the mineral in the hopper without interfering with the free gravity flow thereof 40 through the hopper and without occupying any appreciable hopper space. It has heretofore been proposed to heat the mineral in such hoppers by a blast of steam directed therethrough, but a serious drawback to this 45 method lies in the fact that the moisture in the steam freezes, and makes a bad matter worse, unless the supply of steam is continuously maintained both when the apparatus is operating and when it is idle. Another object of the invention is to provide a heating

means which will avoid the introduction of moisture into the mass of mineral. A still further object of the invention is to provide a heating means that will effect a maximum heat exchange between the heating medium 55 and the material heated thereby, and this object is attained, in the present invention, by extending a heating coil through the lower portion of the hopper, the mineral being heated by radiation from said coil, and leading the discharge end of the coil into the casing of the elevating conveyor, by which the residual heat remaining in the heating medium after it has passed through the coil is transferred to the buckets of the elevating conveyor 60 and to the material in said buckets. To render this practical, without imparting moisture to the material in the conveyor buckets, the heating medium employed consists preferably of the hot products of combustion from a Bunsen oil burner. 65

In order that the improvement may be clearly understood by persons skilled in the art, I have, in the accompanying drawing, illustrated so much of the concrete mixing plant disclosed in my former application above identified as is necessary to illustrate the application thereto of the material heating device, and referring thereto, 75

Fig. 1 is a side elevation, partly in vertical section, of the portable plant;

Fig. 2 is a plan section, turned end for end, on line 2-2 of Fig. 1; and

Fig. 3 is an enlarged horizontal section through the lower section of the casing of the elevating conveyor, in the plane of the line 3-3 of Fig. 1, showing in full lines the discharge end of the heating coil leading through one of the side walls of the conveyor casing. 85

In the present specification I shall not attempt to describe the complete plant, but will limit the description mainly to such parts of the mixing plant as are more or less closely associated with the material heating device. 95 Referring to the drawing, 12 designates as an entirety a rectangular skeleton steel platform, superposed on which is a rectangular material bin comprising a lower section 13 and a removable upper section 14 resting upon 100

the lower section. The platform and superposed sectional material storage bin are shown as supported on wheels for ready portability or blocking when in use on a job. To one 5 end wall of the lower section 13 is suitably attached a cement loading platform 16 in which is swiveled a pilot truck 17, while rear wheels 18 are journaled on suitable axles mounted in the frame members of the floor 10 mounted in the frame members of the floor platform 12.

The lower section 13 of the material bin is equipped with a false bottom, best shown in Fig. 2, the end walls 21 and side walls 22 of which slope downwardly to gate-controlled 15 discharge openings 46 and 47. The space within the upper bin section 14 and the space within the lower bin section 13 above the false bottom is divided approximately centrally, for the separate storage of sand and 20 gravel or crushed stone, by a removable vertical transverse partition 23, this partition extending down to and between the discharge openings 46 and 47 in the false bottom.

Suitably built into one end of the lower 25 bin section 13 is the lower, fixed section 24, of an upright elevator casing, superposed on which is an upper hinged section 25. The inner or front wall of the upper section 25 is pivotally joined to and in register with 30 the inner or front wall of the lower section 24 by hinge lugs 26 and a hinge rod 27 that is supported by a pair of horizontally extending channel bars 28 overlying the lower bin section. For the purposes of the present 35 invention, however, it is immaterial whether the conveyor casing be hinged, so as to be capable of folding down onto the material bin, as indicated by dotted lines in Fig. 1, or be formed in one continuous length. Journaled in the upper and lower ends of the 40 conveyor casing are the usual sprocket wheels 29 and 30 over which is trained the usual endless bucket conveyor 31. At the lower end of the conveyor casing and communicating 45 therewith is a material receiving hopper 33.

The upper end of the conveyor casing is provided with the usual fixed discharge chute 40, and to the latter is hinged at 41 an extension chute 42, which can be lowered, as 50 shown in full lines in Fig. 1, to discharge gravel or crushed stone into the corresponding section of the storage bin, or can be raised to the dotted line position to permit the discharge of sand through chute 40 into the sand 55 section of the storage bin. This extension chute is operated by a cable 43 carried upwardly over the top of the conveyor casing and downwardly of the rear side of the latter, 60 its lower end being anchored to a pin 44 secured in a frame bar of the material storage bin.

The hopper discharge openings 46 and 47 register with underlying spouts 55 and 54 65 which, through a guide chute 59, deliver the

mineral to a mixer (not shown) in the lower compartment 13.

Coming now to a description of the means for heating the material both in the material bin and in the casing of the elevator, 78 designates a U-shaped pipe or coil, the parallel limbs of which extend horizontally through the bin, passing through and supported by both of the end walls 21 of the latter. To one end of this heater pipe is connected a valve-controlled supply pipe 79 leading from a kerosene pressure tank 80 mounted in one corner of the material bin, the upper end of the pipe 79 registering with one end of the coil 78 and being equipped with a gas generating coil 79' and a perforated sleeve 79'' for the induction of air to create a Bunsen flame. The opposite end of the heater pipe 78, as best shown in Fig. 3, enters an opening 81 in one of the side walls of the conveyor casing, whereby the flame and hot products of combustion flowing through the pipe 78 project into the conveyor casing and impart heat to the conveyor and the material being elevated thereby. The portions of the coil 78 extending through the bin hopper are in direct contact with the material in the latter, and, of course, radiate a large amount of heat to the said material. The heating pipe or coil being located substantially at the bottom of the hopper, this radiated heat naturally rises through and warms up the mass of superposed material, thus preventing freezing and caking of the material in sub-freezing weather.

It will be observed by reference to Fig. 3, that the heating pipe 78 enters the conveyor casing at a point opposite the ascending limb of the conveyor. This is an advantage, because the warm products of combustion, which tend to rise, merge into an ascending column of air caused by the upward travel of the conveyor chain and buckets; which would not be the case, were the heating pipe led into the casing at a point opposite the descending limb of the conveyor.

I am aware that it has heretofore been proposed to line the vertical walls of a material hopper with steam pipes or coils; but such heating pipes do not possess the efficiency of horizontal pipes or coils located in the bottom portion of the hopper and embedded in the material stored in the latter. By my improved heater, the heat is distributed throughout practically the entire cross section of the material and rises slowly through the latter, while such heat as is not radiated to the material in the hopper is passed into the elevating conveyor and there transmitted to the material just before the latter is delivered to the hopper. The heating of the conveyor casing in this manner has the further advantage of warming the lubricating oil or grease used for the moving parts of the conveyor, thus reducing the power re-

quired to operate the latter, especially during low temperature periods of operation.

I have found that the usefulness and practical value of the material heating means above described may be substantially enhanced by providing means for retarding escape to the atmosphere of the warm air rising from the hopper and the warm gases issuing from the discharge spout of the conveyor.

10 To this end I extend a pair of cables 99 from the upper front corners of the conveyor casing to the forward upper corners of the material bin, and a similar pair of cables 99' from the upper rear corners of the conveyor 15 casing to the upper rear corners of the material bin; said cables and the top wall of the conveyor casing forming a support for a canopy 100 of heavy canvas or like material, which functions as a heat retaining hood or 20 cover for the bin and conveyor casing. This canopy, especially when made of rubber or rubberized cloth, also serves to exclude rain and snow and facilitates the operation of the machine in stormy and cold weather by preventing wetting and freezing of the stone and sand which would interfere with the free flow 25 of the latter, as well as holding in the heat.

I claim:

1. The combination with a storage hopper 30 for paving material, an upright conveyor casing adjacent to said hopper, and an elevating conveyor in said casing, of means for preventing freezing of material in said hopper and conveyor casing comprising a substantially horizontal pipe extending through 35 said hopper and discharging into said casing, and means for supplying a heating medium to said pipe.

2. The combination with a storage hopper 40 for paving material, an upright conveyor casing adjacent to said hopper, and an elevating conveyor in said casing, of means for preventing freezing of material in said hopper and conveyor casing, comprising a substantially horizontal heating coil extending through 45 the lower portion of said hopper, one end of said coil discharging into said casing at a point opposite the ascending limb of said conveyor, and means for supplying a burning 50 gas to the other end of said coil.

3. The combination with a storage hopper 55 for paving material formed with downwardly and inwardly convergent bottom walls, an upright conveyor casing adjacent to said hopper, and an elevating conveyor in said casing, of a substantially horizontal heating coil in said hopper, said coil extending through and supported by opposed bottom walls with one end thereof discharging into 60 said casing, and means for supplying a heating medium to the other end of said coil.

4. The combination with a storage hopper 65 for paving material formed with downwardly and inwardly convergent bottom walls, an upright conveyor casing adjacent to said hop-

per, and an elevating conveyor in said casing, of a substantially horizontal heating coil in said hopper, said coil extending through and supported by opposed bottom walls with one end thereof discharging into 70 said casing at a point opposite the ascending limb of said conveyor, and a Bunsen burner discharging a heating medium into the other end of said coil.
